(57) **CLAIM**

The ornamental design for an area light with visor frame, as shown and described.

DESCRIPTION

FIG. 1 is an overall perspective view of an area light with visor frame showing my design with a portion of the area light shown in broken lines;

FIG. 2 is a front elevational view of the area light of FIG. 1;

FIG. 3 is a rear elevational view of the area light of FIG. 1 with a portion of the area light shown in broken lines;

FIG. 4 is a top plan view of the area light of FIG. 1 with a portion of the area light shown in broken lines;

FIG. 5 is a bottom plan view of the area light of FIG. 1 with a portion of the area light shown in broken lines; and

FIG. 6 is a left side elevational view of the area light of FIG. 1 with a portion of the area light shown in broken lines, the right side being a mirror image;

FIG. 7 is an overall perspective view of an alternative embodiment of an area light with visor frame showing my design with a portion of the area light shown in broken lines;

FIG. 8 is a front elevational view of the area light embodiment of FIG. 7;

FIG. 9 is a rear elevational view of the area light embodiment of FIG. 7 with a portion of the area light shown in broken lines;

FIG. 10 is a top plan view of the area light embodiment of FIG. 7 with a portion of the area light shown in broken lines; and,

FIG. 11 is a bottom plan view of the area light embodiment of FIG. 7 with a portion of the area light shown in broken lines.

The left side elevational view of the area light embodiment of FIG. 7 is the same as FIG. 6, the right side being a mirror image.

The broken lines in the Figures are shown for illustrative purposes only and do not form part of the claimed design.
